UNITED STATES PATENT OFFICE.

JOHN C. BALLEW, OF EVANSVILLE, INDIANA.

GUIDE FOR MACHINES FOR SAWING HOOPS.

SPECIFICATION forming part of Letters Patent No. 361,979, dated April 26, 1887.

Application filed August 7, 1886. Serial No. 210,274. (No model.) Patented in Canada June 12, 1886, No. 24,279.

To all whom it may concern:

Be it known that I, JOHN C. BALLEW, a citizen of the United States, and a resident of Evansville, in the county of Vanderburgh and State of Indiana, have invented certain new and useful Improvements in Guides for Machines for Sawing Hoops, (for which I have obtained a patent in the Dominion of Canada, No. 24,279, bearing date of June 12, 1886;) and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved guide for hoop-sawing machines. Fig. 2 is a vertical sectional view of the same, and Fig. 3 is a perspective view of the parts of the guide separated.

Similar letters of reference indicate corresponding parts in all the figures.

My invention has relation to guides for guiding hoop-poles to band-saws, so as to cause the said saws to cut the hoop off from the pole, following the outer contour of the pole, making a hoop of a uniform thickness at all points; and it consists to that end in the improved construction and combination of parts of a guide having a roller journaled in a swinging frame parallel to the saw-blade, and having means for twisting the blade to cut parallel with the line of contact of the roller, as hereinafter more fully described and claimed.

In the accompanying drawings, the letter A indicates a U-shaped frame or carrier, which is secured to the frame of the sawing-machine by one of its arms, and which is formed at the ends of its arms with bearings B B, having openings at one side of a less diameter than the diameter of the bearings. A frame consisting of two plates, C C, and two uprights, I I, is journaled in the bearings B B by means of the projections D D upon the plates C C. Each of these projections is provided with a vertical groove or recess, E E, opening in the same direction as the openings in the bearings.

The outer and inner sides of these grooved projections are formed with recesses or apertures F F near their inner ends, the said aper-

tures passing through the sides of the projections and registering with each other, and blocks G, of wood or other soft material, are inserted into the apertures and held secured in them by means of set-screws H, passing through the sides of the apertures.

The uprights I I have their screw-threaded ends J inserted in perforations K in the plates C C near the rear edges, and are secured in them by means of nuts L, bearing against the upper face of the upper plate and the under side of the lower plate, and one of these uprights is formed at its middle with a screw-threaded perforation, N, in which a set-screw, O, or adjusting-screw fits and turns. The end of this screw is journaled in the middle of an upright frame, P, which is formed with grooves Q in the sides near the ends, and slides with these grooved portions in slots R R in the upper and lower plates, C, the said slots opening through the outer edges of the said plates directly in front of the vertical grooves or recesses E E, and the grooved portions fit in the slots, so that the flanges formed outside of the grooves slide upon the outer faces of the plates at the edges of the slots, while the shoulders formed below and above the grooves will slide upon the inner faces of the plates, thus preventing the ends of the frame from binding in the slots when being moved back and forth by the adjusting-screw O.

The outer edge of the frame P is cut out so as to bring the grooved portions to project forward as two arms, and the trunnions of a roller, S, are journaled in the said ends, the roller being thus journaled vertically in the recess formed by the arms of the frame being in a line with the toothed edge of the saw-blade.

The vertical portion of the U-shaped frame or carrier A is provided near its upper end with a cross-piece, T, and two screws, U U, pass through the perforated ends of this cross-piece, and have coiled springs V V secured to yokes W W, swiveled upon the ends of the screws, and these springs are secured at their other ends to the inner edge of the upper plate C, near the ends of the said edge.

The band-saw X passes through the grooved projections of the plates and has the blocks in the said projections bearing against its sides, and the outer side of the roller will at all

times be in a line parallel with the faces of these wooden blocks, and consequently with the sides of the saw.

It will now be seen that when a hoop-pole is fed to the saw the side of the pole will bear against the outer side of the roller, and if the said pole has any uneven places in it the end of the pole is swung around by the operator, so that the outer surface of the hoop is kept at all times parallel with the side of the saw, or as nearly so as possible, the springs permitting the frame to give sufficiently to keep the saw from breaking if it should happen to bind as the hoop is being turned.

By turning the screw passing through the upright of the frame carrying the sliding upright roller the frame may be drawn outward or inward, regulating the thickness of the hoop, and the wooden blocks, which, however, may be of any other soft material which will guide the saw-blade without wearing it, may be adjusted and secured in their apertures or recesses by means of their binding-screws in the sides of the apertures.

Modifications of this guide may be made without departing from the spirit of my invention—such as substituting two parallel rollers in the outer edges of the plates, instead of one roller—and the guide may be used with saws

running in a vertical line or in a horizontal line, the U-shaped frame or carrier being capable of being adjusted and secured to the frame of any machine for sawing hoops.

Having thus described my invention, I claim and desire to secure by Letters Patent of the United States—

1. The combination with a U-shaped frame or carrier having bearings at its ends, of a frame supported in said bearings and carrying a roller, a cross-piece secured to said U-shaped frame, a set-screw at each end of said cross-piece, a yoke swiveled upon the inner end of each of said set-screws, and a coiled spring secured to each of said yokes and to said roller-carrying frame. 45

2. The combination, with a carrier, of a frame supported therein, a roller in said frame, a cross-piece secured to said carrier, a set-screw in each end of said cross-piece, and a coiled spring secured to each of said set-screws and to said frame. 50

In testimony that I claim the foregoing as my own I have hereunto affixed my signature in presence of two witnesses.

JOHN C. BALLEW.
